UNITED STATES PATENT OFFICE.

GEORGE W. MILLER, OF WOONSOCKET, RHODE ISLAND.

MACHINE FOR STRETCHING FABRICS.

SPECIFICATION forming part of Letters Patent No. 259,036, dated June 6, 1882.

Application filed November 1, 1881. (No model.)

To all whom it may concern:

Be it known that I, GEORGE W. MILLER, of Woonsocket, Providence county, Rhode Island, have invented certain new and useful Improvements in Machines for Stretching Cloth, of which the following is a specification.

My invention relates to that class of apparatus used for stretching fabrics; and it consists in the peculiar construction of the stretching reel or cylinder and its adjuncts, whereby I am enabled to stretch shawls and other fabrics which require careful manipulation and cannot, without injury, be subjected to the action of roughened stretching-surfaces.

15. In the drawings, Figure 1 is a plan view of my improved stretching apparatus. Fig. 2 is a longitudinal sectional plan; Fig. 3, a cross-section on the line 1, 2, Fig. 2, looking in the direction of the arrow 1.

20. Upon the fixed shaft A revolves the reel or cylinder B, composed of any suitable number of disks *a a* and longitudinal connecting-bars *b*, forming a light open cylindrical cage. Upon the shaft A are fixed inclined arbors D, on 25 which turn wheels E, the radial arms *d* of which extend through the spaces between the bars *b*, and from each arm projects a sharp-pointed pin, *e*. The arbors D are so set that the wheels E are inclined toward each other 30 at one side, as shown, and the fabric X is presented to the cylinder at that point where the peripheries of the wheels are nearest and leaves the cylinder at the point where they are farthest separated. As the fabric is presented to

35 the cylinder the pins *e* penetrate the same, and as the fabric is drawn forward the cylinder and wheels revolve, the pins gradually separate,

and the fabric is stretched until it reaches the point where it is withdrawn. As the pins are small and sharp and only penetrate the fabric 40 at the edge, it will not be injured in stretching, the bars *a* presenting but a small surface, little liable to abrade or wear the material, and not capable of retaining any considerable body of dust or of working the latter into the fabric. Moreover, as the fabric is carried over the reel any dust or foreign particles will fall 45 through the cylinder to the floor. There is little or no friction upon the material in drawing it over the supporting-surface. 50

As it is desirable to hold the fabric at the edges only, and as the fabrics are of different widths, I secure the arbors D by set-screws *s* adjustably to the shaft, the slatted cylinder permitting the wheels to be set at any required 55 distance apart without affecting their relative action.

Other means of adjusting the wheels may be employed.

I claim—

The combination, in a stretching-machine, of a cylinder, turning on a fixed shaft, A, and consisting of parallel disks *a a* and connecting longitudinal bars *b*, and wheels E, turning on inclined arbors D upon the shaft, and provided 60 with arms extending between the bars and carrying points *e*, substantially as set forth.

In testimony whereof I have signed my name to this specification in the presence of two subscribing witnesses.

GEORGE W. MILLER.
